CENTRALIZED TRAFFIC CONTROLLING
SYSTEM FOR RAILROADSWilliam D. Hailes, Brighton, N. Y., assignor to
General Railway Signal Company, Rochester,
N. Y.

Application October 31, 1934, Serial No. 750,828

14 Claims. (Cl. 246—3)

This invention relates to centralized traffic controlling systems for railroads, and more particularly pertains to the use of transmission lines in the communication part of such systems.

5 A centralized traffic controlling system for railroads usually places a central office in communication with a large number of outlying field stations in such a way that controls may be transmitted to these field stations for the governing of 10 the operation of traffic controlling devices located at the several stations, and also, for the transmission of indications from the station to the central office to advise the operator of the location of trains and the condition of the traffic controlling 15 devices.

In such a system, irrespective of whether it is of the direct wire type or of the selector type, it is usually preferable to provide the source of energy for the transmission line circuits at the central 20 office, as the battery source, or other current supply, can then be maintained with greater efficiency and accuracy. With this arrangement of current supply, it usually occurs both in direct wire type systems and in selector type systems that there 25 are difficulties to be overcome because of the inherent inductive and capacitive characteristics of a relatively long transmission line extending from the central office to the outlying field stations.

The present invention proposes to so associate 30 communication systems of the above described character with their line circuits as to overcome the difficulties encountered.

In one situation, it is desired to have a transmission line extending from a central office to an outlying field station, or stations, which completes a 35 circuit for a source of energy and a relay in the central office in such a manner that this circuit is controlled by an open or closed contact at the outlying field station. With this arrangement, it 40 usually occurs both in direct wire type systems and in selector type systems that the sequence of events is such that the distributed capacity of the transmission line connecting the control office with the field station becomes discharged, so that 45 the application of energy at the central office results in a temporary surge of current which is conveniently termed the charging current. A charging current flows irrespective of whether the line circuit is opened or closed at the field station 50 from which an indication is to be received.

It has been found that in some instances the charging current that flows into an open circuited line reaches a peak value considerably greater than the current that normally flows under the steady conductive conditions of the line 55

circuit and that this charging current surge lasts for an appreciable length of time. Under these conditions a relay inserted in the line, for the purpose detecting the closed conductive condition of the line, has been undesirably picked up by the 5 charging current when it was supposed to remain in the released position in accordance with the open circuit condition of the line.

The present invention proposes to provide means in cases of this type wherein the transmission line may be charged, prior to the insertion of the indication receiving relay at the central office into the transmission line circuit connecting the central office with the field apparatus.

Other objects, purposes and characteristic features of the present invention will be in part obvious from the accompanying drawings, and in part pointed out, as the description of the invention progresses.

In describing the invention in detail, reference 20 will be made to the accompanying drawings in which like reference characters provided with distinctive exponents designate corresponding parts, and in which:

Fig. 1 illustrates in a diagrammatic and conventional manner the embodiment of the present invention in a direct wire type of indicating systems; and—

Fig. 2 illustrates in a diagrammatic and conventional manner the application of the present invention to the line circuits of a selector type communication system, as disclosed, for example, in the pending application of Judge et al, Ser. No. 640,062, filed October 28, 1932.

Figs. 3 and 4 illustrate in a diagrammatic and conventional manner parts of the control office apparatus in a selector type communication system as disclosed, for example, in the pending application of Judge et al., Ser. No. 640,062, filed October 28, 1932.

Fig. 5 illustrates in a diagrammatic and conventional manner parts of a field station in a selector type communication system as disclosed, for example, in the pending application of Judge et al., Ser. No. 640,062, filed October 28, 1932.

For the purpose of simplifying the illustration and facilitating in the explanation, the various parts and circuits constituting the embodiment of the invention have been shown diagrammatically and certain conventional illustrations have been 50 employed, the drawings having been made more with the purpose of making it easy to understand the principles and mode of operation, than with the idea of illustrating the specific construction and arrangement of parts that would be employed 55

in practice. Thus, the various relays and their contacts are illustrated in a conventional manner, and symbols are used to indicate connections to the terminals of batteries, or other sources of electric current, instead of showing all of the wiring connections to these terminals.

The symbols (+) and (-) are employed to indicate the positive and negative terminals respectively of suitable batteries, or other sources 10 of direct current; and the circuits with which these symbols are used, always have current flowing in the same direction. When alternating current is used in place of direct current, the particular symbols employed represent the relative instantaneous polarities.

For the purpose of disclosing the present invention, it has been shown applied to a unit direct wire system in Fig. 1 and to a selector type of system in Fig. 2. As the particular advantages 20 of the present invention will be best understood by a description of both types of systems, a detailed description of Figs. 1 and 2 will be given separately.

Unit wire system

25 In a unit wire system, (see Fig. 1) each device to be indicated in the central control office is usually provided with a separate circuit. This may be accomplished by providing an individual wire 30 for each device with a common return wire for all devices. On the other hand, individual line circuits may be provided for each device to be indicated. In either case, the application of the present invention is the same.

35 As one embodiment of the present invention, a section of track TK having the usual closed circuit type of track circuit with a track relay T and a track battery 4 has been shown as having its occupied or unoccupied condition transmitted 40 to the control office. Connecting the field station at which the track relay T is located, and the control office are two line wires 13 and 15 of a suitable transmission line. These line wires 13 and 15 form a circuit which is supplied with 45 current from a line battery 18 located in the central control office.

In the control office, an impulsive relay 1E is provided with control contacts 5 and 6. Contact 5 controls an impulse repeating relay 2E which is 50 provided with a control contact 7.

The control contact 6 determines whether the line circuit shall be opened or closed, while the control contact 7 of relay 2E shifts the line circuit from the charging circuit including the resistor CR, to the lower winding of the indication detecting or receiving relay ME. The control contact 7 may be of the make-before-break type, if desired, so as to shift the line circuit from a charging resistor CR to the lower winding of a 55 message receiving relay ME without allowing a momentary open circuit condition during which a precharge might leak off due to line leakage, as later explained in detail.

60 The impulsive relay 1E is controlled by a manually operable self-restoring push button K. Another manually operable self-restoring push button CK is employed to cancel a message or indication previously received by the message receiving relay ME by opening its stick circuit.

65 An indication lamp I is associated with the message receiving relay ME to display to the operator the particular condition of the outlying track relay to be indicated, although it is to be understood that any other type of indicating means 70

might be employed and still be within the contemplated scope of the present invention.

It is believed expedient to point out the sequence of operations, and operating features in connection with Fig. 1 at this time. However, the 5 electrical characteristics of Figs. 1 and 2 will be considered together.

Operation of Fig. 1.—With the system in its normal condition, as illustrated, and the track section TK unoccupied, the track relay T is normally energized as in all normally closed circuit type of track circuits. Assuming that this unoccupied condition of the track section TX existed upon the last action of the operator to ascertain the condition of the track section, the indication 15 lamp I is not illuminated and all of the relays in the control office are deenergized.

Let us assume that the operator desires to ascertain or check the condition of the track section TK while it is still unoccupied. To do this, he 20 actuates the key K to a depressed position which applies energy to the impulsive relay 1E by a circuit apparent from the drawing. The response of the contact 6 of relay 1E connects the positive terminal of the battery source 18 to the line wire 25 15 through front contact 6, back contact 7 of relay 2E, charging resistor CR, to the line wire 15. Thus, the line wires 13 and 15 are connected to their respective terminals of the battery 18, but a conductive circuit is not completed by reason of 30 the open condition of back contact 17 of the track relay T.

Assuming that the back contact 17 of the track relay T has been closed subsequent to the last energization of the line circuit, then any charge 35 which may have been stored in the distributed capacity of the transmission line has been dissipated, so that the application of the terminals of the battery source 18 to the transmission line causes a charging current to flow until the distributed capacity of the transmission line is substantially charged by the potential of the battery. 40

It is noted that this charging current flows 45 through the charging resistor CR which is preferably of the non-inductive type. The resistance value of this resistor CR is preferably such as to permit the distributed capacity of the line circuit to be sufficiently charged within the desired time, and still have sufficient resistance to prevent excessive current flow in case the line circuit should have a short circuit or was conductively closed by the back contact 17 of the track relay T. The relation of the charging resistor CR to the charging current and the time at which the impulsive relay 2E may be shifted to include the relay ME in the line circuit will be considered more in detail hereinafter. 55

The closure of front contact 5 of the impulsive relay 1E energizes the impulse repeating relay 2E by a circuit obvious from the drawings. This impulse repeating relay 2E is of the slow acting type, that is, it is slow in picking up but may be quick in dropping away although this is not necessary to provide for the proper operation of the system. The pick-up time for the impulse repeating relay 2E is sufficiently long to allow for the charging of the distributed capacity of the transmission line to the desired degree before the contact 7 shifts 60 from a back point to a front point to include the lower winding of the message receiving relay ME in the line circuit.

When the distributed capacity of the transmission line is substantially charged, there is sub- 70 75

stantially no current flow when the contact 1 shifts the line circuit to include the lower winding of the relay ME. As the line circuit is conductively open due to the open condition of back 5 contact 17 of the track relay T, the relay ME remains deenergized and the indicator lamp I remains unilluminated advising the operator of the unoccupied condition of the track section TK.

The momentary actuation of the key K by the 10 operator is usually sufficient to cause the successive energization of the relays 1E and 2E as the charging of the transmission line and the inclusion of the relay ME occur in such rapid sequence. Should the timing characteristics of the combination 15 involved be such as to require a longer time period, then the relay 1E can be made extremely quick in picking up but much slower in releasing, so that its releasing period will be of sufficient duration for the picking up of relay 2E and the 20 charging of the line circuit.

Now let us assume that the track relay T is deenergized with its back contact 17 closed. Then upon the closure of the front contact 6 of the relay 1E following the manual actuation of the key 25 K, the transmission line is energized through the charging resistor CR. Upon the picking up of the contact 1 of the impulse repeating relay 2E, the lower winding of the relay ME is included in the circuit. With the back contact 17 of the track relay T closed, the current flow is of a value above the pick up value of the relay ME during the time that the contacts 6 and 7 are picked up, which causes the contacts of the relay ME to be actuated to energized positions.

35 With the contacts of the relay ME picked up, a stick circuit is closed from (+), through a circuit including the front point of the manually operable cancelling key CK, front contact 11 of the relay ME, upper winding of the relay ME, to (-). This stick circuit maintains the relay ME energized dependent upon the actuation of the cancelling key CK. Under such conditions, the indicator lamp I is energized through front contact 40 9 of the relay ME so long as this stick circuit is closed, irrespective of the fact that in the meantime the back contact 17 of the track relay T may again open. It is of course obvious, that relays 1E and 2E sequentially release following the release of the key K after having accomplished 45 their allotted functions.

50 Should the operator desire to ascertain the condition of the track section TK following the reception of an occupied indication, he first actuates the cancelling key CK, which deenergized the stick circuit of the relay ME to extinguish the indicator lamp I, and then actuates the manually operable key K to allow the indicator lamp I to be controlled in accordance with the occupied or unoccupied condition of the track section TK, as 55 above described.

It should be noted, that the distributed capacity between the line wires 13 and 15 may be discharged due to two reasons, namely, the closure 60 of back contact 17 of the track relay T while the terminals of the battery 18 are removed from the two line wires 13 and 15, or due to the leakage of the charge from the wires during a protracted period of deenergization of the line circuit although the back contact 17 of the track relay T is open.

Selector type system

(See Fig. 2)

75 The line circuits of a selector type system, such

as disclosed in the pending application of Judge et al, Ser. No. 640,062, filed October 28, 1932, have been shown in Fig. 2 with the present invention applied thereto. This application of Judge et al is the basis and corresponds to the disclosure of 5 the British Patent No. 419,399, dated October 28, 1932, and filed under the provisions of the International Convention, to which reference may be made for details of operation of the system, although it is believed that the understanding of 10 the invention and the system with which it is associated may be readily obtained in connection with the drawings of the present application and the description in connection therewith. All of the parts mentioned in the present application 15 which correspond to the disclosure of such prior application of Judge et al, and the corresponding British patent, have the same reference characters so as to provide ready identification of such corresponding parts.

20 In a system of this character, the field stations and control office are interconnected by four line wires 10, 12, 14 and 16. The line wires 10 and 12 are connected together at the last field station in the system and are energized with positive and negative impulses from a control battery CB in the control office for the purpose of transmitting the controls and for the purpose of causing the synchronous step-by-step operation at the control office and at the several field stations.

25 At the control office, a series of stepping relays 1V, 2V, 3V and LV together with a half-step relay VP (see Fig. 4) operate step-by-step in response to the time spaced impulses impressed on the line circuit. Likewise, at the field station a series of stepping relays 1V¹, 2V¹, 3V¹ and LV¹ together with a half-step relay VP¹ (see Fig. 5) operate the step-by-step in response to the time spaced impulses impressed upon the line circuit.

30 The line wire 10 includes a three-position polar 40 relay F (with suitable exponent) at the control office and at each field station which repeats the impulses of each series. The particular polarity of the impulses of each series placed upon the control and stepping circuit is determined by 45 polarity selecting relays PC and NC which determine respectively whether the impulses are positive or negative in character. These relays PC and NC are operated in accordance with the station code calls and the controls to be transmitted, 50 as shown in Fig. 3 of the accompanying drawings, so that one or the other of these relays is energized for each step taken by the stepping relays in the control office. The duration of each impulse 55 of a series as well as the time spaces between such impulses is determined in accordance with the operation of an impulsive relay EP and its controlling relay E which is operated in response to the operation of the stepping relays 1V, 2V, 3V 60 and LV together with the half-step relay VP (see Fig. 4).

65 At the control office, each impulse is repeated by the relay F, but irrespective of the polarity of such impulse, it is also repeated by a line repeating relay FP. A relay 2FP is provided for repeating the relay FP. A slow acting relay SA is provided for marking off the different series of impulses by being picked up at the beginning of each different series and by dropping at the end 70 of each series. This is accomplished by providing that the relay SA is slow in picking up upon the first impulse of each series but is relatively much slower in dropping away so as to maintain its point contacts closed during the time spaces 75

between impulses in each series of impulses. The relay SA is also provided with a repeater relay 2SA.

Similar relays are provided at each of the field stations, but for convenience, only the relays F¹, FP¹, SA¹, and SB¹ have been shown at one field station which is typical of all field stations.

The relay 2FP in the control office directly operates the stepping relays 1V, 2V, 3V and LV to 5 take one step for each deenergization of the line circuit and to cause the relay VP to operate to 10 an opposite position for each energization of the line circuit. It will be apparent that this operation is dependent upon the picking up of the 15 relay SA which occurs on the first impulse of a cycle of operation and is maintained throughout such cycle of operation so that the stepping relays may be stuck up until the end of such cycle. At the field station, similar operation occurs, but 20 the stepping relays are operated directly from the relay FP¹ dependent upon the picking up of the relay SB¹ and the closure of a front contact 134 of the station selecting relay SO¹ or front contact 171 of the lockout relay LO¹. These station 25 relays will be mentioned more in detail hereinafter.

In Fig. 3, a cycle controlling relay C is shown as controlled by a starting button 1SB, that is, each time the button 1SB is actuated, picking up 30 a code determining relay 1CD, the pick up circuit for the cycle controlling relay C is closed so as to cause the system to transmit controls, all of which has been disclosed in detail in the above mentioned prior application. The cycle 35 controlling relay C when picked up together with the code determining relay 1CD renders the relays PC and NC over buses 47 and 48 subject to the code jumpers 58, 55 and 40 and the control lever SML successively on the steps marked off 40 by the stepping relays 1V, 2V and 3V. It is of course to be understood that the buses 45, 56, 59 and 61 extend to other code determining relays so as to be controlled in accordance with other code jumpers and control levers for other stations 45 corresponding to such other code determining relays, only one of which may be picked up at any one time.

The indication line circuit comprising the line wires 14 and 16 is energized from an indication 50 battery IB and has included therein at the control office, message receiving relays MF and MB which are respectively controlled through front and back contacts of the relays FP and 2FP, as well as through front and back contacts respectively of a dividing relay DV controlled by the 55 relay EP.

A charging resistor CR^a is provided for similar purposes, as explained in connection with the resistor CR of Fig. 1.

60 The indication line wire 14 extends to all of the field stations normally including a back contact, such as back contact 156 of the lock-out relay LO¹, at each of the field stations.

When a particular field station is transmitting, 65 the lock-out relay LO¹ at that station is picked up as well as the slow acting repeating relay SA¹ with its repeating relay SB¹, thereby rendering the open or closed conductive condition of the indication line circuit dependent upon the control of either the relay PF¹ or PB¹ in accordance with whether the stepping line circuit is energized or deenergized.

The pulsing relay PF¹ and PB¹ are positioned on each step taken by the step-by-step means 75 (including the relays 1V¹, 2V¹, 3V¹, LV¹ and VP¹)

in accordance with the station code assigned to that station and indications to be transmitted, such indications being illustrated as associated with a track relay T and a signals-at-stop relay M. The initiation of the system for the transmission of indications occurs upon a change in indication conditions by the dropping of a change relay CH¹ which is restored after the system is once set into operation.

In the control office suitable station registering relays are controlled by the relays MB and MF of which the station registering relay 2ST has been indicated. This station registration has been merely indicated, as it is sufficient to understand that a particular station registering relay 15 is picked up corresponding to the station code received. Following the selection of a station relay, the indications are transmitted so that the relays MF and MB control indication registering relays of which relays 1RF and 1RB have been 20 illustrated as controlled over buses 230 and 233 which may be connected to other indication storing relays by other station registering relays. The relay 1RB is shown as controlling an indicator OS through its contact 233.

25 It is of course to be understood that there is often considerable distance between the central control office and the outlying field stations, and it is for those cases in which the distributed capacity in the line circuit is sufficiently great to 30 cause troublesome line charging surges that the present system is proposed to be employed.

Although only a part of the whole communication system has been disclosed, it is believed that the features of the present invention will 35 be readily understood in connection with the following description of the operation, it being understood that the features relative to a communication system of this character have been fully disclosed in the above mentioned application of Judge et al, Ser. No. 640,062, filed October 28, 1932.

Operation of Fig. 2.—Under normal conditions, the line circuits are deenergized and the communication system is at rest. Upon the initiation 45 of the system from either the control office or a field station by the actuation of a starting button such as button 1SB or by the dropping of a change relay such as relay CH¹, a series of impulses of distinctive polarities is placed 50 upon the stepping line circuit to comprise a cycle of operation. The characters of these impulses are determined in accordance with code jumpers and control levers so as to select a particular station and determine the controls for that station, when the system is initiated by the actuation of a starting button such as button 1SB. The code jumper or control lever for each step through suitable circuit means picks up either the PC relay or the NC relay for that step depending upon whether the particular impulse for such step is to be positive or negative in 55 character.

For a cycle of operation for the transmission of indications alone, the impulses placed upon 65 the stepping line circuit are all of one character, so that one of the polarity determining relays is picked up at the beginning of a cycle and is maintained picked up until the end of that cycle. This is accomplished by the picking up of the 70 relay FC through the medium of the indication line circuit upon the dropping of relay CH¹. The indication line circuit includes relay MB by reason of the closed contacts 176 and 206 in multiple with contact 158 of relay 2SA which does not 75

pick up until near the end of the first impulse. Closure of front contact 162 of relay MB energizes the pick up circuit for relay FC. The picking up of relay FC prevents the relay C from being picked up (by means not shown) so that the bus 48 for the relay NC is continuously energized from (+), through back contact 41 of relay C and front contact 166 of relay FC.

At the beginning of a cycle of operation, 10 regarding the type of cycle, one of the polarity determining relays PC or NC is picked up thereby placing an impulse upon the stepping line circuit. This is repeated by the line relays F (with suitable exponents) at the control office 15 and at each field station as well as by their respective line repeating relays FP (with suitable exponents). After this impulse has been applied for a predetermined period of time sufficient 20 for the slow acting relays SA and SB at the control office and at each field station to be picked up, the stepping circuit is opened by the contact 52 of relay EP. When a sufficient period has elapsed for the time space following the first impulse, the back contact of relay EP 25 is again closed.

In brief then, the contacts 50, 51, 53, and 54 of the relays PC and NC act as pole changing contacts so that particular polarities are placed upon the stepping line circuit from the control 30 battery CB; while the back contact 52 of relay EP is intermittently operated to space the impulses of a cycle. It may be stated in this connection, that the relays PC and NC assume their positions while the back contact 52 of relay EP 35 is open, but remain in static or steady conditions during the time that the back contact 52 is closed.

As previously mentioned, the relay FP in the control office repeats each impulse placed upon 40 the stepping line circuit by reason of circuits closed by the contact 61, irrespective of the character of energization of the line relay F. Similarly, each energization of the relay FP is repeated by the relay 2FP by reason of the closure 45 of its front contact 68. Also, the front contact 69 of the relay 2FP controls the relay SA, as previously described. At the field station, the relay FP¹ repeats the line relay F¹ by reason of its control by contact 101.

50 During the first part of a cycle, the relay SO¹ and the relay SOS¹ are selectively picked up and selectively maintained picked up throughout the cycle in accordance with the code so that if the cycle of operation is for the transmission of controls to that station, then the relay SO¹ remains picked up and causes, through its contact 134, the stepping relays to operate throughout the cycle of operation. If, however, the cycle of operation is for the transmission of indications, 55 the relay LO¹ has been picked up by the relay CH¹ so that contact 171 is closed throughout the cycle of operation causing the stepping operation to continue. Thus, irrespective of whether it is a cycle for the transmission of both controls and indications, a cycle of operation for the transmission of indications alone, or a cycle of operation for the transmission of controls alone, the stepping relays operate when such station is sending and/or receiving for such cycle. However, the features of the present invention relate more particularly to the indication transmission so that the operation for the transmission of indications will be considered more particularly.

75 At the beginning of a cycle following the re-

sponse of the relay SA to the first impulse which is slightly longer than the rest, the relay DV is subject to the relay EP. In other words, each time the relay EP is deenergized to cause an impulse, the relay DV is energized by reason of a circuit from (+), through front contact 177 of relay SA, back contact 178 of relay EP, windings of relay DV, to (-).

Now assuming that at the beginning of the cycle, the relays LO¹ and SB¹ are picked up so 10 that the field station is conditioned to transmit, then during each time space in the series of impulses, the positive terminal of the indication battery IB is connected to the line wire 14 through the lower winding of relay MB and the 15 indication circuit is dependent for its closed or open conductive condition upon the front contact 191 of the relay PB¹. More specifically, assuming the front contact 191 of relay PB¹ to be closed, a circuit is completed from the positive terminal of the indication battery IB, through a circuit including back contact 157 of relay DV, lower winding of relay MB, back contact 206 of relay FP, back contact 176 of relay 2FP, line wire 14, front contact 156 of relay LO¹, 25 front contact 172 of relay SB¹, back contact 173 of relay FP¹, front contact 191 of relay PB¹, resistor 2R¹, line wire 16, to the negative terminal of the indication battery IB. It is noted that contact 158 of relay 2SA is open throughout 30 the cycle of operation after the first impulse, so that the contacts 176 and 206 are entirely effective with respect to the control of relay MB.

On the other hand, during each impulse placed upon the stepping line circuit, the indication line 35 circuit is dependent for its closed or open conductive condition upon the contact 199 of the relay PF¹. For example, assuming the contact 199 of relay PF¹ to be closed, the indication line circuit is closed from the positive terminal of the 40 indication battery IB, through a circuit including front contact 157 of relay DV, lower winding of relay MF, front contact 175 of relay FP, front contact 176 of relay 2FP, line wire 14, front contact 156 of relay LO¹, front contact 172 of relay 45 SB¹, front contact 173 of relay FP¹, front contact 199 of relay PF¹, resistor 2R¹, line wire 16, to the negative terminal of the indication battery IB.

In other words, during the time spaces of each 50 series of impulses, the message receiving relay MB is controlled in accordance with the opened or closed condition of the front contact 191 of the relay PB¹; but, during the impulses of each series the message receiving relay MF is controlled in accordance with the opened or closed condition 55 of contact 199 of relay PF¹.

For each time space in a series of impulses placed upon the stepping line circuit, a step-by-step mechanism at the control office and at each field station is caused to take one step. Through the medium of contacts on the step-by-step mechanism, the relays PF¹ and PB¹ at the field station are caused to be selectively energized in accordance with the positions of devices from which indications are desired in the control office. The relay PF¹ is positioned during a time space in accordance with the indication it is to transmit on the next impulse period; while the relay PB¹ is positioned during each impulse period in accordance with the indication it is to transmit on the next time space. Thus, on each step taken by the step-by-step mechanism at a field station, the relays PF¹ and PB¹ govern the indication line circuit.

Similarly, the message receiving relays MB and 75

MF are effective to control indication storing relays on each step taken by the step-by-step mechanism in the control office. More specifically, the message receiving relay MB is positioned during each time space marked off on the stepping line circuit in accordance with the position of contact 191 of the relay PB¹, for example, and this position is maintained during the following energized period of the stepping circuit so as to suitably position an indication storing relay in accordance with its energized or deenergized condition during such impulse period.

Likewise, the relay MF is positioned in accordance with the position of contact 199 of relay PF¹, for example, during each impulse period marked off on the stepping line circuit, and this condition of the relay MF is maintained during the following time space so as to properly position during such time space an indication storing relay. These relays MB and MF control their respective indication storing relays during the proper periods marked off on the stepping line circuit as rendered effective by the step-by-step mechanism at the control office by their contacts 210 and 217 which usually apply positive or negative potential depending upon their released or picked up positions to their respective indication storing relays. However, it is believed unnecessary to discuss in detail the operation of the step-by-step mechanisms and the indication storing relays for an understanding of the present invention, as such means has been disclosed in various prior applications, as for example, the application of Judge et al., Ser. No. 640,062, filed October 28, 1932, above mentioned.

During the shift from one period to another, that is, from an impulse period to a time space period, or vice versa, there is an interval of time during which the indication line circuit is not energized from the indication battery IB, and during which the distributed capacity of the indication line circuit may become discharged by reason of the closed condition of one of its controlling contacts at a field station. This is because the field station apparatus is not permitted to change the condition of the indication line circuit until after the indication line circuit is opened at the control office, which is necessary to provide that the message receiving relays will be properly controlled. Then, the transfer at the field station occurs so that upon the closure of the indication line circuit at the control office, the conductive circuit then established is dependent upon the governing contact at the field. From this it is obvious that a charging current will flow at the beginning of each period which follows a period during which the indication line circuit has been conductively closed at the field station.

Let us consider the conditions for an impulse period with the relays DV, F, FP, 2FP and FP¹ picked up. Then the relay MF is energized or not dependent upon the closed or open condition of the contact 199 of the relay PF¹. Let us assume that the contact 199 of the relay PF¹ is closed, but the contact 191 of the relay PB¹ is open. Thus, the relay MF will be energized and its contact 217 will be picked up.

Upon the picking up of the contact 52 of the relay EP to mark the end of the impulse period, the relay DV is deenergized by the opening of the back contact 178 of the relay DV, so that the indication battery IB is removed from the indication line at substantially the same time that the line

relays F (with suitable exponents) assume deenergized positions.

As the contact 157 of the relay DV assumed a dropped away position at substantially the same time that the line relays F assume deenergized positions, then the indication line circuit is deenergized at the control office prior to the shift from contact 199 to the contact 191 at the field station by the dropping of relay FP¹. We have assumed that the contact 199 is closed and that the contact 191 is open. With the source of current supply 1B removed from the line circuit, the closed condition of the contact 199 discharges the stored energy in the distributed capacity of the line circuit comprising line wires 14 and 16.

As the relay 2FP repeats the relay FP, its contact 176 assumes a back point position slightly after the contacts 175 and 206 of the relay FP assume their back point positions. The release period for the relay 2FP is preferably of sufficient duration to provide for the charging of the distributed capacity, and its contact 176 preferably assumes a dropped away position slightly after the operation of the contact 173 of relay FP¹ to a back point position, so that when the contact 176 assumes its position, the line circuit has been changed and is governed in accordance with the contact 191 of relay PB¹.

The charging resistor CR^o provides a circuit from the positive terminal of the battery 1B, through the back contact 175 of the relay FP and the front contact 176 of the relay 2FP (just before it operates), to the line wire 14 which allows a charging current to flow to charge the distributed capacity in the transmission line circuit. This charging current charges the distributed capacity of the line to a sufficient value prior to closure of back contact 176, so that the charging surge of current is below the pick-up value of the relay MB upon the closure of back contact 176.

It is readily apparent that similar conditions, as above described, occur during the transition from the time space period on the stepping circuit to an impulse period, but such conditions may be understood by analogy, it being thought sufficient to only point out the charging circuit. When the change is made from the branch including the relay MB and contact 191 to the branch including relay MF and contact 199, the precharging circuit includes the resistor CR^o, front contact 206 of relay FP and back contact 176 of relay 2FP.

In brief, during the transfer from one branch of the line circuit to the other, the distributed capacity of the line circuit may become discharged due to the closed condition of the contact governing the conductive circuit for the first branch, but the distributed capacity for the line circuit is precharged through the charging resistor CR^o before the relay for the second branch is inserted into the circuit to thereby provide that it will be governed in accordance with the conductive condition of that branch and not operated by a surge. In other words, a precharging circuit is completed for charging the distributed capacity of the line circuit whenever the relays FP and 2FP are out of correspondence and just prior to the insertion of a message receiving relay in the line, to thereby prevent or eliminate the maximum current flow of charging current through the line relay, which would result in certain cases in a false indication.

It will be apparent from the above description that, after the transfer is made from one branch to another with the contact governing the con-

ductive circuit at the field station for the second branch closed, the indication receiving relay for that branch is energized through a conductive circuit having a normally steady current value 5 sufficiently above the pick-up value for the indication relay for that branch to cause it to assume the energized position.

For example, the relay MF is energized by a circuit closed from the positive terminal of battery IB, through a circuit including front contact 157 of relay DV, lower winding of relay MF, front contact 175 of relay FP, front contact 176 of relay 2FP, line wire 14, front contact 156 of relay LO¹, front contact 172 of relay SB¹, front contact 173 of relay FP¹, front contact 199 of relay PF¹, compensating resistor 2R¹, return line wire 16, to the negative terminal of the battery IB.

Similarly, the relay MB is energized by a circuit closed from the positive terminal of the battery IB, through a circuit including back contact 157 of relay DV, lower winding of relay MB, back contact 206 of relay FP, back contact 176 of relay 2FP, line wire 14, front contact 156 of relay LO¹, front contact 172 of relay SB¹, back contact 173 of relay FP¹, front contact 191 of relay PB¹, compensating resistor 2R¹, return line wire 16, to the negative terminal of the battery IB.

It may be noted that the compensating resistor 2R¹ is of a value consistent with the distance of the field station from the central office in comparison with the distance of the more remote field stations from the central office. In other words, the resistance of the indication line circuit is maintained the same irrespective of whether the back contact 156 of the relay LO¹ is closed, allowing some distant station to transmit, or whether front contact 156 of relay LO¹ is closed allowing the first field station to transmit.

A wire with negligible resistance could be substituted for the charging resistor CR⁰, but it is desirable to use sufficient resistance to prevent excessive current flow in case there should be a short circuit between line conductors 14 and 16 near the control office and to avoid unnecessarily large current flow if the controlling contacts at the field location are closed prior to inserting the indication receiving relay. Therefore a value of resistance for resistor CR⁰ is chosen so that the line will be sufficiently charged in the desired time and so that excessive current flow will not take place under the circumstances described above. It is to be understood that the time allotted for charging the line is a matter of design and that it is made long enough to permit the line to be sufficiently well charged before inserting the indication receiving relay.

60 Discussion of electrical characteristics

This discussion of electrical characteristics of the circuits above described is merely for the purpose of making clear the relationship of the charging resistors of the present embodiment of the invention with the operating values of the relays and their time characteristics. It is to be understood that the charging resistors in circuits having particular characteristics and associated with relays having particular characteristics must have their resistance values determined in accordance with the particular values involved, and such resistance values may be determined either by experiment or by calculation. The following discussion is intended to bring out

certain relationships, irrespective of the values which are involved in the application of the present invention, and irrespective of whether the particular values and characteristics of the circuits are determined experimentally or by calculation.

With reference to both Figs. 1 and 2, the system in each case connects the charging resistor CR in series with the transmission line and the contacts at the field station. With such an arrangement, the characteristics of the circuit may be considered as including only distributed capacity and resistance in series, as the mutual inductance between the line wires is of such a small value as to be negligible for practical purposes.

It is preferable that the charging resistor shall be maintained in the circuit to charge the distributed capacity until the charging surge of current has risen to its peak value and then decreased below the pick-up value of the relay to be inserted, which insures that the relay will not respond if the circuit is not conductively closed at the field station.

However, it should be noted in this connection that the pick-up value of a relay is usually considered the steady current value and disregards the time which is required to operate its armature from a released position to an actuated or energized position. Thus, a momentary energization of the relay with current of a value slightly above the pick-up value for a time period less than that required to overcome the inertia of the armature for that particular degree of energization would be ineffective to actuate the relay. In other words, if the surge value of a charging current rises above the pick-up value of a relay but is of insufficient duration to overcome the inertia of the relay, then it is immaterial if such rise above the pick-up value occurs. But, where a transmission line has a fairly large value of distributed capacity, the peak value of the charging surge of current is of such a high value and is existent for such a long period of time, as to usually cause the operation of a line relay employed in connection therewith.

In view of the above, it is apparent that if the pick-up current value for a particular relay is considered to be its steady current operating value, then it may be possible to insert it into the line circuit slightly before the surge value of the charging current recedes or decreases below such pick-up value. However, it is preferable that the surge value should decrease below the pick-up value before the insertion of the indication detecting relay, so that any superimposed surges, which might be incurred during a transfer from the charging circuit to the relay winding, might not effect an operation of the relay armature.

It is also desirable to insert the indication detecting relay before the charging current has decreased to zero or a steady value dependent upon the leakage of the line to minimize the delay. This is especially true in the case of a selector system, as shown in Fig. 2, where such a delay would be multiplied many times by reason of the large number of successive transmitting periods in each cycle.

Also, it should be noted in this connection that under certain conditions line circuits have a leakage current which flows depending upon the insulation of the line circuit. In other words, after the application of a potential to a line circuit having appreciable leakage, a current flows which rises to a peak value and then decreases to a steady value dependent upon the leakage of the

line circuit. The leakage current obviously must be well below the pick up value of the indication detecting relay.

The lower the resistance value of the charging resistor in the charging circuit, the more quickly will the desired charged condition be obtained, but it is desirable to maintain the resistance of the charging resistor substantially equal to the resistance of the corresponding windings of the line relays to be inserted, so that, when a closed conductive circuit exists while the charging resistor is included in the circuit, an excessive current flow will not occur.

As the resistance value of the charging resistor is raised, the peak value of the charging surge of current is lowered, but the time required for the peak value to recede or decrease below the pick-up value of the relay to be inserted is increased. Therefore, the particular resistance value of the charging resistor is dependent upon the time in which it is desired to charge the distributed capacity before the transfer is made to insert the line relay, and its minimum value is dependent upon the current which is likely to flow under conductive circuit conditions if the charging resistor is maintained in the circuit for an appreciable period of time.

General summary

From the above description, it will be readily apparent that the present invention provides means in connection with a line circuit having distributed capacity whereby that distributed capacity may be precharged, so to speak, before a relay is included therein to register its constant current conditions. It is, of course, also apparent that the various timing characteristics and sequence of events either in a unit wire system or in a selector system might vary so as to cause the distributed capacity to be discharged at various times and for various reasons other than those described, but the present invention contemplates that means may be provided in such systems in accordance with the circumstances to be met in such a way that when a message receiving relay is included in the line the operation of this relay will depend upon whether or not the line is closed and will not be operated by unauthorized currents such as occur when a discharged open circuit line is connected to the source of potential.

Although the principles of the present invention have been applied to embodiments having precharged circuits of the distributed capacity type, it is to be understood that the invention may be applied to circuits having lump capacities or condensers associated therewith without in any way departing from the contemplated scope of the present invention.

Having thus described a communication system with a line circuit arranged in accordance with the present invention, as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the appended claims.

What I claim is:—

1. In combination with a line circuit having

distributed capacity, a source of energy, a line relay, means for at times including said source and said line relay in series in said line circuit, and means for precharging the distributed capacity of said line circuit from said source each time before said source and said line relay are included in series in said line circuit. 5

2. In combination with a line circuit having distributed capacity, a relay, means effective to at times insert said relay into the line circuit, 10 and means for precharging the distributed capacity of the line circuit each time said relay is included therein.

3. In combination; two stations; a line circuit connecting said stations and inherently having distributed capacity; a contact at one station for controlling said line circuit at that station; a relay, a source of current and a compensating resistor at said other station; and means at said other station for at times including said resistor 20 and said relay in series in said line circuit successively in that order, whereby the distributed capacity of said line circuit is charged before said relay is included in said circuit.

4. In combination, a control office, a field station, a line circuit connecting said field station and control office and having distributed capacity, a track relay at said field station for opening or closing said line circuit at said field station, a source of current in said control office, a line relay in said control office, a compensating resistor in said control office, and means for at times inserting successively said compensating resistor and said line relay in that order in series with said source and said line circuit. 35

5. In combination, a control office, a field station, a line circuit connecting said field station and control office and having distributed capacity, a track relay at said field station for opening or closing said line circuit at said field station, a source of current in said control office, a line relay in said control office, a compensating resistor in said control office, means for at times inserting successively said compensating resistor and said line relay in that order in series with said source 40 and said line circuit, whereby said line relay is controlled in accordance with said track relay when inserted in said line circuit, and indicator means controlled by said line relay. 45

6. In combination, a line circuit distinctively controlled from a remote point during a plurality of successive time intervals, a line relay, a source of current supply, and means at a local point for inserting said source of current supply and said line relay successively in series in said line circuit during certain of said successive time intervals. 55

7. In combination, a line circuit distinctively controlled from a remote point during a series of measured time intervals, two line relays, means for including said line relays alternately in series in said line circuit during successive time intervals, means for charging the distributed capacity of said line circuit just prior to the inclusion of each particular one of the line relays in said line 60 circuit, and other means controlled in accordance with the conditions of said line relays during that time interval.

8. In combination, a line circuit, a source of energy, a line relay, means for at times inserting said relay in said line circuit in series with said source, and means for inserting said source in series in said line circuit each time before said line relay is inserted. 70

9. In combination, a line circuit having dis- 75.

tributed capacity and at times open circuited and at times closed circuited, a line relay, and means for excluding said line relay from said line circuit when the condition of said line circuit changes but for including said line relay in said line circuit when the condition of said line circuit is stable.

5 10. In combination with a line circuit having distributed capacity, a source of energy, a line relay, means for at times inserting said source and said line relay in series in said line, means for charging the distributed capacity of said line circuit just prior to each time said line relay and said source are inserted in series in said line circuit and other means for controlling the conductive condition of said line circuit to thereby control said line relay.

15 20. 11. In combination, a line circuit, means causing said line circuit to be opened or closed at a remote point, a line relay and a source of energy at a local point, means at said local point for inserting said source of energy in said line circuit, and means for adding said line relay in series with said source in said line circuit after said 25 source has been inserted for a short interval of time.

25 30. 12. In combination, a circuit having capacity included therein, contact means for conductively opening and closing said circuit, a source of energy, control means for at times inserting said source of energy into said circuit, a relay for detecting the open or closed conductive condition of said circuit, and means for adding said relay to said circuit each time said source is inserted, 35 said means delaying momentarily after the operation of said control means, to thereby allow sufficient time for the capacity to become charged before said relay is added.

40 45. 13. In combination, step-by-step means at a control office and at a field station operated in synchronism, a line circuit having distributed capacity and connecting the control office and field station, means at the field station for selectively opening and closing said line circuit on each step of said step-by-step means in accord-

5 10. 15. 20. 25. 30. 35. 40. 45. 50. 55. 60. 65. 70. 75. 80. 85. 90. 95. 100. 105. 110. 115. 120. 125. 130. 135. 140. 145. 150. 155. 160. 165. 170. 175. 180. 185. 190. 195. 200. 205. 210. 215. 220.
